UNITED STATES PATENT OFFICE.

PATRICK J. SULLIVAN, OF NEW YORK, N. Y.

DESIGN FOR A HORSESHOE.

SPECIFICATION forming part of Design No. 22,794, dated September 19, 1893.

Application filed August 24, 1893. Serial No. 483,887. Term of patent 7 years.

To all whom it may concern:

Be it known that I, PATRICK J. SULLIVAN, of Brooklyn, in the county of Kings and State of New York, have invented and produced a new and useful Design for Horseshoes; and I do hereby declare that the following is a full and exact description thereof, reference being had to the accompanying drawing, and to the letters of reference marked thereon, making a part of this specification.

My invention relates to horse-shoes and particularly to light-weight shoes such as are used for racing purposes, and its object is to produce a novel and useful design.

The accompanying drawing presents a perspective view of an inverted horse-shoe embodying my design. The general shape of the shoe may be as usual, the bar of which the shoe is formed being thin and flat for the greater portion of its length, as is common in racing-shoes.

The special features of the design are the

enlargement A on the under side of the front of the shoe, said enlargement having beveled or inclined ends a, a, and slightly rounded edges a', a', and the enlargement B on the under side of the side or quarter of the shoe, said enlargement B having beveled or inclined ends b, b, and rounded or beveled edges b', b'. The shoe has also the heel calks D, D', with beveled or inclined ends d, d', the faces of the enlargements and the heel calks being in the same plane.

I claim as my invention—

The design for a horse-shoe, substantially as shown and described.

In testimony whereof I have signed my name to this specification in the presence of two subscribing witnesses.

PATRICK J. SULLIVAN.

Witnesses:

A. N. JESBERA,
A. WIDDER.
